(57) **CLAIM**

The ornamental design for a lubricant dispense meter, as shown and described.

DESCRIPTION

FIG. 1 is a top elevation view of the lubricant dispense meter;

FIG. 2 is a bottom elevation view thereof;

FIG. 3 is a left side elevation view thereof and is a mirror image of the right side.

FIG. 4 is a front elevation view thereof;

FIG. 5 is a rear elevation view thereof.

FIG. 6 is a front perspective view thereof; and,

FIG. 7 is a rear perspective view thereof.
